(57) **CLAIM**

The ornamental design for set of legs for a platform bed as shown and described.

DESCRIPTION

FIG. 1 is a top perspective view of a set of legs for a platform bed, showing my new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a bottom perspective view thereof shown within a frame of a platform bed;

FIG. 10 is a top perspective view thereof; and,

FIG. 11 is a left side elevation view thereof.

The broken lines depict environmental subject matter that forms no part of the claimed design.

The set of legs for a platform bed is shown with symbolic breaks. The appearance of any portion of the article between the break lines forms no part of the claimed design.
